YOGHURT MAKING APPLIANCE

Jacques Gairard, Selongey, France, assignor to
SEB, Selongey, France

Filed July 5, 1974, Ser. No. 486,198

Claims priority, application France Jan. 22, 1974

Term of patent 14 years

Int. Cl. D7—04

U.S. Cl. D7—96

FIG. 1

FIG. 2

FIG. 3

FIG. 4

FIG. 5

FIG. 6

FIG. 7

FIG. 8

FIG. 1 is a top perspective view of a yoghurt making appliance showing the rear and one side of my new design;

FIG. 2 is a top perspective view thereof showing the front and other side;

FIG. 3 is a bottom perspective view thereof;

FIG. 4 is a top plan view thereof;

FIG. 5 is a top perspective view thereof in an open condition;

FIG. 6 is an elevational view of FIG. 5 showing the front of the base and cover;

FIG. 7 is a side elevational view thereof; and

FIG. 8 is an exploded perspective view.

I claim:

The ornamental design for a yoghurt making appliance, as shown.
